UNITED STATES PATENT OFFICE.

ROBERT R. THOMPSON, OF BLOOMINGTON, ILLINOIS.

MATTRESS-STUFFING MACHINE.

SPECIFICATION forming part of Letters Patent No. 611,294, dated September 27, 1898.

Application filed July 12, 1897. Serial No. 644,184. (No model.)

To all whom it may concern:

Be it known that I, ROBERT R. THOMPSON, a citizen of the United States of America, residing at Bloomington, in the county of McLean and State of Illinois, have invented certain new and useful Improvements in Mattress-Stuffing Machines, of which the following is a specification.

My invention relates to improvements in mattress-stuffing machines of the same general class as the machine shown in United States Patent No. 520,170, issued to me May 22, 1894, the object of the present invention being to combine with the frame, bed, and plunger of the machine shown in that patent a new and improved top or cover and a new and improved gate, together with novel means for operating said cover and gate.

The invention is fully described and explained in this specification and shown in the accompanying drawings, in which—

Figure 1 is a side elevation of an entire machine embodying my invention. Fig. 2 is a front end elevation thereof, the view being in the direction indicated by the arrow *x*, Fig. 1. Fig. 3 is a transverse vertical section of the machine through the line 3 3, Fig. 1, the view being in the same direction as in Fig. 2. Fig. 4 is an enlarged side elevation of the front portion of the machine, showing the delivery end of the box, the oscillating gate, and the means for raising and lowering one corner of the top or cover, the top or cover being at its highest limit of movement. Fig. 5 is a similar view showing the top or cover partly depressed, the delivery end of the machine and the gate being omitted. Fig. 6 is a longitudinal vertical section of the front portion of the machine, including the delivery end and the oscillating gate. Fig. 7 is an enlarged front elevation showing one of the corner-posts of the machine and one of the oscillating levers for raising and lowering the top. Fig. 8 is a view, partly in horizontal section and partly in top plan, showing the delivery end of the box, the oscillating gate, and one of the supporting-brackets on which the gate is pivoted. Fig. 9 is a perspective view of a portion of the gate, showing the sector-shaped oscillating casting and pivot at one of the ends thereof. Fig. 10 is a view, partly in plan and partly in horizontal section, of cer-

tain portions of the machine, the line of section being shown at 10 10 in Fig. 11; and Fig. 11 is a vertical cross-section in line 11 11 of Fig. 10, the top or cover being shown in its lowered position.

In the views, A A A A are four posts of suitable height placed at the angles of the rectangular main frame of the machine embodying my invention, and A' A' are short posts in rear of the main frame supporting certain operating parts, all the posts being joined and braced by suitable horizontal members in any manner adapted to form a rigid structure. Between the posts of the main frame is a suitably-supported solid platform A², forming the bottom of the box of the machine, and on this bottom are supported two parallel longitudinal side boards B B, provided with brackets B' B', arranged in pairs at the ends of the machine, the brackets of each pair being connected by a transverse right-and-left-hand screw *b*, (see Figs. 10 and 11,) and both the screws being connected by means of sprocket-wheels *b'* and a sprocket-chain *b*², whereby they may be simultaneously operated for the purpose of moving the side boards symmetrically inward or outward to vary the width of the box thus formed. Upon the bottom of the box rests a laterally-expansible plunger C, provided with a rearwardly-extending bar C', having a dependent nut in engagement with a longitudinal screw S, extending from end to end of the frame of the machine and operated by suitable mechanism, the rotation of the screw being adapted to move the plunger forward and back in the box formed by the bottom and the movable side pieces. All the elements thus described are substantially the same as the corresponding parts shown in my prior patent, No. 520,170, referred to above. Above the box thus described is a rectangular frame E, moving freely up and down and provided at its angles with clasps *e e*, embracing the corner-posts A A and adapted to hold the frame in suitable relation to the posts and box, and beneath this rectangular frame and supported thereby is a top or cover made up of a central solid section F and expansible and compressible sections F' F', fastened to the edges of the solid section and adapted to be expanded or contracted, so as to give the entire cover a width equal to the space be-

tween the side pieces B B in any given adjustment thereof. The expandible sections of the cover may be provided with any suitable means for engaging the side boards when the cover is down for the purpose of insuring the equal adjustment of the box and cover. As a suitable means of so connecting the cover and side boards the side edges of the cover are shown in Fig. 11 of the drawings as provided with downwardly-open hooks or clamps f, adapted to embrace the side boards, so that their inward or outward movement may give an equal movement of adjustment to the variable sections of the cover.

15 The expandible portions of the cover shown herein have the same construction as the expandible parts of the cover in the machine shown in my prior patent above referred to; but in the device shown in the said prior patent the expandible portion of the cover is at its center and the non-expandible parts are at the edges. The construction shown in this application is an improvement over the prior construction for the reason that in the older device the heavy non-expandible parts of the cover were moved inward or outward at each adjustment of the width of the cover, whereas in the construction shown herein the central solid portion is never moved laterally, the adjustment of the cover requiring only the inward or outward movement of the comparatively light expandible parts supported at the sides of the central solid portion.

35 The entire rectangular frame E is supported by four approximately vertical bars G G G G, pivoted to the side pieces of the frame near their ends, each of the vertical bars being provided with a series of holes g g, as shown in Fig. 1, for the purpose of varying the relation of the bars to the frame and thereby varying the limit of depression of the frame and the cover supported by it. Each of the bars has in its outer margin two notches g' g², the notch g' in each bar being 40 a considerable distance above the notch g² and the inner portion of each of the notches being extended both above and below its outwardly-open slot or throat. Immediately above the notches g' g² on each bar are corresponding latches l l', pivoted to the inner face of the bar and swinging freely on their pivots. Below the bed or bottom of the box of the machine are two transverse shafts H H, extending across the frame of the machine 45 and, as shown, adapted to be synchronously rotated by means of a longitudinal shaft H', worms mounted on said shaft, worm-gears mounted on counter-shafts H² and engaging said worms, and gearing connecting the counter-shafts with the shafts H H. The longitudinal shaft H' may be rotated in any desired manner, as by mounting a crank on one of its ends or by providing suitable means for applying power for its rotation, and the 50 gearing for transmitting rotation to the transverse shafts H H may be varied in any desired manner to give them suitable speed.

On the ends of each of the shafts H H are rigidly mounted two levers K K, each provided with one long and one short arm lying 55 on opposite sides of the shaft, the outer ends of each lever being provided with eccentric bosses k k', from the faces of which project corresponding pins p p', adapted to enter and engage the notches g' g² of the corresponding vertical bar G. The oscillating levers K K, with their eccentrics k k' and pins p p', are intended and adapted to raise and lower the bars G G and the frame and cover to which the bars are attached, the operation by which 60 such raising and lowering is effected being as follows: As shown in Figs. 1 and 4, the cover is in its highest position, the pin p at the end of the longer arm of each of the levers K being in engagement with the shoulder formed 65 by the upper side of lowermost notch g² in the corresponding bar G, and the lower end of each of the bars G being pressed outward or in the direction indicated by the arrow x' by means of a spring S, attached to the frame E 70 and pressing against the bar, as clearly shown in Figs. 1 and 4. The eccentric boss k on the longer arm of each of the levers extends from the pin p toward the shaft H or axis of the lever, while the eccentric boss k' at the end 75 of the short arm extends away from said axis, so that when the bosses are in the position shown in Figs. 1 and 4 each of the bosses extends downward from its pin. If now the transverse shafts H H be so rotated as to swing 80 the longer arms of the levers K K inward, giving to each lever the movement in the direction indicated by the arrows on the pins p p' in Fig. 4, such a movement will evidently lower the pin p of each lever and the bar 85 thereon supported and correspondingly raise the pin p', and this movement of inversion of the lever will turn the eccentric bosses k k' upward from their pins p p' instead of downward, this position of the parts being indicated in Fig. 5. Each of the eccentric bosses k k' lies in the vertical plane of the latches l l', and the latches are so placed that when in the movement just described the boss k at the end of the long arm of the lever has been 90 completely inverted it is pressed against the lower edge of the corresponding latch l', so as to raise the latch and the bar G and free the pin p from contact or engagement with the upper margin of the notch g² in the bar. 95 This entire movement brings the pin p' into the notch g' in the bar, as shown in Figs. 5 and 6, the cover being now in the position shown in full lines in Fig. 6. The further movement of the levers K K carries the bars G G still 100 farther downward and brings the cover into the position indicated in dotted lines in Fig. 6, thereby completing its downward movement, for the purpose hereinafter set forth. This entire movement of the levers brings 105 each of them into approximately the position shown in Fig. 4, each of the bars G being, however, in its lowest instead of its highest position, and the cam l above the notch g'

of each bar being immediately above the eccentric h' at the end of the short arm of the corresponding lever. The reversal of the movement of the shafts H H and levers K K reverses the movement of the bars G G and the cover with its supporting-frame, the bars and cover being forced upward to the position shown in Figs. 1, 2, 3, and 4.

The mechanism and operation thus described for raising and lowering the cover constitute a great improvement over the means for the same purpose shown in my prior patent, in which the cover is shown as hinged at one of its ends and is raised by a comparatively slow operation. The raising of the entire cover in a constantly horizontal position is in itself an improvement, and the celerity with which it may be raised or lowered is a still further advantage.

On the front end of each of the side pieces B B of the box is a forwardly-extending plate D, preferably flush with the inner face of the side piece and formed with an arc-shaped slot d , as most clearly shown in Fig. 6. Across the front of the frame of the machine is an angle-bar D', lying immediately below the front portions of the plates D D, and on this angle-iron is supported the central portion of the sheet-metal bottom of a forward extension of the box, adapted to receive a tick in the process of filling or stuffing. To the front portion of each of the plates D D is fastened a sheet-metal side piece B² and one of the inwardly and outwardly adjustable side portions A³ of the bottom of the forward extension of the box, each of the plates D D being movable inward and outward with the side piece B, to which it is fastened, and the corresponding parts B² A³ of the extension being correspondingly movable for the purpose of securing lateral adjustment of the extension to correspond with the lateral adjustment of the box proper. The cover F F' extends forward in front of the frame of the machine as far as the front end of the sheet-metal extension supported by the plates D D and angle-iron D', the front end of the cover being thin or wedge-shaped, as shown in section in Fig. 6, and being adapted to form the top or cover of the extension.

On the front faces of the front posts of the frame of the machine are brackets M M, extending forward toward the end of the sheet-metal extension of the box, and on the inner faces of these brackets are sector-shaped castings N N, pivoted at their centers to the front ends of the brackets and extending backward, as clearly shown in Figs. 6 and 8. The sector-shaped castings N N are attached to the respective ends of an oscillating sheet-metal gate O, supported by the castings and swinging with them about their pivots in the brackets M M. This gate is a segment of a cylinder corresponding in curvature to the arc-shaped slots d in the plates D D and swings freely in said slots without touching their edges, the position of the gate being de-

termined wholly by the position of the pivoted oscillating sectors N N, to which it is fastened. The inner faces of the posts A A are preferably recessed, as shown in Fig. 8, to receive the sectors, in order that the side pieces B B may be adjusted outwardly into contact with the posts, if desired, and the lower edge of the gate O may be formed with an inwardly-turned flange o for the purpose of stiffening it, if desired. The pivot or gudgeon on one of the sectors N N may be extended outward through the corresponding bracket to permit the attachment of a crank or other means for oscillating the gate, such a projecting squared gudgeon being shown in Fig. 9. This gate is extremely simple, strong, and easily operated, and it has certain other advantages over the gate shown in my prior patent or any gate shown in any structure of this general class or in any press of any kind within my knowledge. The gate is of such width that when in its highest position its upper edge reaches the extreme limit of height of the box, and at the same time it moves so easily that the pressure of the cover in its descent readily depresses the gate to any desired extent, its upper margin, however, being held constantly in contact with the lower face of the cover. Furthermore, in the operation of the machine, which is that of stuffing mattresses, the end of the mass of material within the box when pressed against the convex face of the gate assumes a slightly-concave form, which makes it fill the end of the tick more perfectly than is possible when the gate is plane.

The operation of the machine, which is substantially the same as that of my prior machine, may be briefly described as follows: The upper ends of the bars G G being adjusted with relation to the cover and its frame so as to give the cover the desired distance above the bottom of the box, the cover is raised to the position shown in Fig. 1 and the gate is raised to the position shown in Fig. 6. The material with which the mattress is to be stuffed is then placed in the box and properly distributed, after which the cover is lowered completely, giving the material a suitable vertical pressure and depressing the gate, as above described. The plunger is then pressed forward, compressing the material longitudinally to any desired degree, after which the end gate is swung completely out of the slots in the plates D D, leaving the box and its extensions open from end to end. The mattress-tick having been slipped upon the extension at the front end of the box, the forward movement of the plunger is continued until the material is completely ejected from the box and its extension and forced into the tick, which is thereby filled. This completes the operation of stuffing the tick, and the cover may be again raised to repeat the operation.

It will be observed that the means shown and described herein for raising and lower-

ing the top are such as to give the top in its upward or downward movement a varying speed, the upward movement of the top being slowest at its beginning and the downward movement of the top being slowest at its close. This is especially important in the downward movement, since it permits the rapid lowering of the top until the point at which the compression of the material in the box begins, after which time the movement is slow and the power correspondingly great.

Having now described and explained my invention, what I claim as new, and desire to secure by Letters Patent, is—

15 1. The combination with a framework and top vertically guided therein, of a series of approximately vertical supporting-bars pivoted to the top and having a series of shoulders upon one side, a series of operating-levers 20 pivotally mounted upon the frame and having means of engagement with said shoulders, means for retaining said bars in engagement with said lever and means for disengaging one of said shoulders from the lever at about 25 the time at which said lever engages with the next succeeding shoulder; substantially as described.

2. The combination with a framework and the press-box having laterally - adjustable 30 sides supported therein, of extensions upon said sides provided with arc-shaped slots, brackets upon the framework and a segmental gate pivoted by means of suitable radial arms upon said brackets and adapted to swing in 35 said slots whereby the press-box may be contracted laterally without adjustment of said gate; substantially as described.

3. In a mattress-stuffing machine the combination with a supporting-frame and a press-box having a suitable bottom and sides, of a top guided vertically in the frame, approximately vertical bars supporting the top, shafts journaled in the frame and provided with means for their rotation, and levers mounted on the ends of said shafts and each projecting on both sides of the shaft on which it is mounted, each of said levers being provided at both its ends with means for detachably engaging the corresponding supporting-bar and each bar and lever, at each point of mutual engagement being provided with means whereby the rotation of the lever may slightly vary the point of support of the bar upon the lever.

4. The combination with the frame, the press-box and the vertically-movable cover, of the bars, G, G, the shafts H, H, the levers, K, K, and the cams and eccentrics, l, l', k, k', the ends of each lever being adapted to detachably engage the corresponding bar at 60 points contiguous to the cams, l, l', and the cams being adapted to rest upon the eccentrics in suitable positions of the levers, thereby slightly shifting, in each case, the point of support of the bar upon the lever. 65

In witness whereof I have hereunto set my hand, at Chicago, in the county of Cook and State of Illinois, this 6th day of July, A. D. 1897.

ROBERT R. THOMPSON.
